UNITED STATES PATENT OFFICE.

LOUIS P. REICHERT AND ANDREW FULLER, OF BUFFALO, NEW YORK.

STOP-COCK BOX FOR WATER OR GAS PIPES.

SPECIFICATION forming part of Letters Patent No. 358,696, dated March 1, 1887.

Application filed April 17, 1884. Serial No. 128,296. (No model.)

To all whom it may concern:

Be it known that we, LOUIS P. REICHERT and ANDREW FULLER, both of the city of Buffalo, in the county of Erie and State of New 5 York, have invented new and useful Improvements in Stop-Cock Boxes for Water and Gas Pipes, of which the following is a specification.

This invention relates to an improvement in the extensible or telescopic tubular boxes 10 which are placed in the ground over the street-cocks of water and gas pipes for the purpose of giving access to the cocks when required.

The object of our improvement is to produce a simple, light, and durable box of this character; and our invention consists, to that end, 15 of the improvements, which will be hereinafter fully set forth, and pointed out in the claim.

In the accompanying drawings, Figures 1 and 2 are vertical sectional elevations of our 20 improved stop-cock box. Figs. 3 and 4 are horizontal sections in lines *xx* and *yy*, Fig. 1, respectively.

Like letters of reference refer to like parts in the several figures.

25 A represents the upper and B the lower tubular part of the box. The upper part, A, is fitted loosely over the lower part, B, so that the former can be freely raised and lowered or turned on the latter in adjusting the length of 30 the box.

a represents horizontal depressions, and *b* represents vertical depressions or grooves formed in the upper tubular part, A, on the inner side thereof.

35 *c* represents studs or projections formed on diametrically-opposite sides of the lower part, B, near its upper end. The vertical grooves *b* are arranged on diametrically-opposite sides of the upper part, A, so as to receive the studs 40 *c* of the lower part, B. The ends of the horizontal grooves *a* open into the vertical grooves *b*, so that upon turning one tubular part with reference to the other the studs *c* can pass out of the vertical grooves *b* into the horizontal 45 grooves *a*. The latter are made of such size as to confine the studs against vertical movement. Upon adjusting the parts A and B so that the studs *c* project into the grooves *b* the part A can be raised and lowered on the part 50 B to adjust the height of the box.

When the parts have been adjusted, they

are locked in position by turning the part A on the part B so that the studs *c* enter the horizontal grooves *a*. The grooves *a* and *b* do not increase the thickness of the metal, but 55 form corrugations in the part A, which is made of substantially the same thickness throughout, thereby forming a light and strong box.

D represents a hollow ear or extension formed on one side of the upper part, A. 60

E represents the cover, which rests on the top of the upper part, A, and is provided with a lug or tongue, *e*, which projects into the hollow ear D when the cover is in place.

f is a vertical screw passing through the ear 65 D, and held against vertical movement by heads *f'* *f''*, bearing, respectively, against the upper and lower sides of the ear D, the portions of the screw *f* which are seated in the top and bottom plate of the ear D being formed 70 without screw-threads.

G is a follower arranged in the ear D, underneath the tongue *e*, and provided with a screw-threaded opening in which the screw *f* works. The rear side of the follower G is 75 made straight and bears against the straight rear side of the ear D, whereby the follower is prevented from turning and compelled to rise or descend upon turning the screw *f*. The cover E is locked in position by turning the 80 screw *f* so as to press the follower against the under side of the ear *e*, and is released by a reverse movement of the follower.

H represents the elongated flaring base or foot formed at the lower end of the lower part, 85 B, and provided in its flattened sides with notches or openings *h*, to enable the base to straddle the service-pipe.

i represent horizontal plates or flanges cast on the inner side of the base H at both ends 90 of thereof, and on opposite sides of the notches *h*, to give the box a firm support in the ground and prevent the surrounding soil as much as possible from working into the lower part of the box, whereby the stop-cock would be obstructed.

Our improved construction of the box reduces the weight, and consequently the cost, of the box materially without sacrificing strength, and permits the parts to be easily molded and 100 cast. It also protects the box to a large extent against moisture and consequent rusting

by reason of the upper and outer portion of the box conducting the moisture down toward the foot of the box, and preventing the moisture from coming in contact with the interlocking parts on the inner side of the box.

5 We claim as our invention—

The combination, with the upper tubular part, A, provided with a hollow ear, D, of the

cover E, provided with a tongue, e, a screw, f, seated in the ear D, and a follower, G, applied to said screw, substantially as set forth.

LOUIS P. REICHERT.
ANDREW FULLER.
